UNITED STATES PATENT OFFICE.

ROY O. McQUEEN AND JOSEPH A. BATSON, OF MEMPHIS, TEXAS.

FUEL-VALVE LOCK FOR MOTOR-CARS.

1,371,975.

Specification of Letters Patent. Patented Mar. 15, 1921.

Application filed July 12, 1920. Serial No. 395,551.

To all whom it may concern:

Be it known that we, ROY O. McQUEEN and JOSEPH A. BATSON, citizens of the United States, residing at Memphis, in the 5 county of Hall, State of Texas, have invented certain new and useful Improvements in Fuel-Valve Locks for Motor-Cars; and we do hereby declare the following to be a full, clear, and exact description of the invention, 10 such as will enable others skilled in the art to which it appertains to make and use the same.

This invention relates to valves, and more especially to locks for the same; and the 15 object of the invention is to produce an extremely simple valve and lock mechanism for application to the gasolene line of a motor car between its tank and carburetor, so that it is necessary to insert a key and 20 give it a quarter turn in order for the gasolene to flow, and it is necessary to turn the key to close the valve and shut off the flow of gasolene before the operator can remove the key when he is about to leave his car.

25 Details of the preferred construction of this attachment are set forth below and shown in the drawings wherein:

Figure 1 is a front elevation.

Fig. 2 is a rear elevation.

30 Fig. 3 is a horizontal section.

Let B designate a board such as that on which the instruments are mounted or one of the floor boards, and let G designate the pipe through which the gasolene flows from 35 the tank to the carburetor.

The numeral 1 designates a valve casing closed at its rear end and provided with lateral nipples 2 which are inserted into the gas line G when the latter has been cut for 40 the application of this attachment. Near its forward end the casing is internally threaded as at 3, then shouldered as at 4 and smooth as at 5, and around its smooth portion it is preferably threaded as at 6. The valve plug 45 10 fits rotatably within the bore of the casing and has through its rear end a passage 12 adapted to align with the two nipples when the valve is open so that the gas may flow. Near its front end the plug is reduced 50 to form a shoulder 14, forward of which it is extended as at 15 and made angular at its extremity as by a nick 16.

The lock 20 is preferably of the cylindrical type capable of being operated by the 55 insertion of a key 21 and its rotation for

90°, and its details are unimportant. At its rear end this lock is externally threaded as at 23 to fit the threads 3 in the casing 1, and its rear extremity is chambered as at 25 to receive the extension 15 of the plug. The 60 rotary element of the lock (not shown) is connected with the plug where the latter is made angular or nicked as at 16. Interposed between the annular end 24 of the lock and the shoulder 14 of the plug is a thrust 65 bearing, of balls or otherwise, as shown at 26; and therefore when the lock is screwed into the casing as far as possible, the plug is held in the casing by said thrust bearing quite reliably and is yet permitted to rotate. 70

The numeral 30 designates a shell having a cylindrical body internally threaded as at 36 to engage the external threads 6 on the casing, and with its front end closed except for an opening 32 which closely receives the 75 front end of the lock 20 and exposes the keyhole as shown in Fig. 1. The rear end of the shell has a flange 33 pierced with holes 34 through which may be passed bolts 35 having nuts 37 on their inner ends behind 80 the board B or other element to which the device is attached.

When the parts are assembled as seen in Fig. 3, it is obvious that by inserting the key and turning the plug its passage 12 may be 85 set in line with the nipples to permit the gas to flow. When the owner is about to leave his car, he turns the key for 90° which closes the valve, and only then may he withdraw the key. If he prefers to leave the car 90 without turning off the gas, he may do so. While we have spoken of a key-actuated lock, it is obvious that the lock could be of any appropriate type so long as its barrel 95 was constructed with reference to the other parts as described herein.

What is claimed is:

1. The combination with a valve including a casing having aligned nipples adapted to be let into a pipe, the rear end of the casing being closed and the front end provided with threads on its exterior, and a rotary plug within said casing having a passage adapted to be set in line with said nipples and its front end made angular at its extremity; of a cylindrical lock inserted in the front end of said casing and connected with the angular extremity of the plug, and a shell whose body is internally threaded to engage the external threads on the casing, 110

whose front end incloses said lock, and whose rear end has a flange to be mounted on a support.

2. The combination with a valve including a casing having alined nipples adapted to be let into a pipe, the rear end of the casing being closed and the front end provided with threads on its exterior and interior, and a rotary plug within said casing having a passage adapted to be set in line with said nipples and its front end reduced to form a shoulder and made angular at its extremity; of a lock externally threaded at its rear end to engage the internal threads

in the casing and adapted for connection 15 with the angular end of its plug, a bearing between the lock and the shoulder on such plug, and a shell engaging the external threads of the casing and having an opening in its front end for said lock. 20

In testimony whereof, we affix our signatures, in the presence of two witnesses.

ROY O. McQUEEN.
JOSEPH A. BATSON.
